MEANS FOR WAVING HAIR

Ralph L. Evans, New York, and Everett G. McDonough, Mount Vernon, N. Y., assignors to Zotos Corporation, New York, N. Y., a corporation of New York

Application July 5, 1934, Serial No. 733,758

18 Claims. (Cl. 132—36.2)

Our invention relates to the art of producing a so-called "permanent wave" in hair, and particularly to devices employed as absorbents during the process of imparting such a wave.

5 In the treatment of hair, it is usual to surround a preformed tress with a wrapper, consisting of an absorbent material alone or combined with a paper or parchment sheet and/or a foil sheet.

The absorbents heretofore used in the construction of the different commercial forms of 10 wrappers have usually been either cotton flannel or felt, but in their natural state these materials absorb solutions or water slowly and must be specially treated to increase the rate of absorption; their capacity is small so that they must be 15 relatively thick and they do not readily give up their moisture when pressed; moreover, their use has the economic disadvantage of being expensive and many attempts have been made to find a 20 cheaper substitute.

To this end, blotting paper has been tried but as an absorbing agent it has not been successful due to its low absorptive capacity, retentiveness 25 of moisture or solution absorbed, or its non-pliability and difficulty of handling.

We have found that by taking two or more 30 sheets of thin easily-wetted paper and by maintaining them in close contact, either mechanically, adhesively or otherwise, we can obtain an absorbent whose water absorbing capacity is materially increased over that of the individual sheets 35 and can be varied widely by varying the number of sheets of paper used, or by varying the character of the paper itself or both. This absorbent readily takes up water or a solution and easily gives it up when slightly pressed or squeezed. It 40 is very pliable and quite easy to handle.

Our invention utilizes not only the natural absorbing characteristics of the paper itself, which 45 enables it to absorb water or a solution within and between its fibers, but it also utilizes the capillary forces acting on the water or solution between the sheets themselves to absorb an additional amount of water or solution over that absorbed by the individual sheets. Moreover, since 50 the absorbing capacity due to capillary forces is a function of the total area of the surfaces involved, our invention further contemplates increasing this capacity without increasing the size 55 of the sheets by increasing the actual surface area per unit over-all area of the sheet as by crimping or creping or by forming indentations, pockets, or corrugations in the surfaces, which has the additional effect, due to overlapping of

superposed layers or sheets, of forming recesses in which additional water or solution is held.

We have found that crimped paper held together by embossing very satisfactorily meets the conditions specified. Any form of embossing, such as the all-over, point, line, design or other type, may be advantageously employed but we have found the so called "crepe paper", with its many small crimps and creases held together by whipcord embossing, to be particularly efficient, for 10 the crimps and creases form pockets which hold water or solution additional to that held by the fibers and by capillary attraction. Such pockets may be specially designed.

We have found that the several thin layers or 15 sheets of paper may be satisfactorily held together by the interlocking effect produced by embossing, or by an adhesive, preferably at spaced intervals, or, again, by mechanical means; for instance, by staples, clips, brads or sewing. 20

Our absorbent, consisting of two or more thin 25 paper sheets, held together in the manner above indicated, may be used as the absorbent unit without further addition but to render it more durable, prevent stretching, particularly when 30 wet and to facilitate handling, we prefer to reinforce it with a material imparting body strength thereto. We have found that pliable 35 sheets of parchment, paper, foil, Cellophane, cloth, glassine and similar thin flexible materials, possessing adequate tensile strength, are well suited to this purpose. These sheets may be perforated, if desired, and may be attached to the absorbent in any suitable manner, as by any of the means indicated above for attaching the 40 multiple sheets together, but we prefer to use a backing sheet attached by an all-over glue application since it forms an excellent bond, firm 45 and of neat appearance.

The above indicated characteristics of our invention pre-eminently fit it for use in pads employed in the process of giving a permanent wave to hair, both by the machine and by the machineless methods, and make possible the simplification of pad structures by the elimination of the 45 extra flap which may be employed to cover flannel or felt absorbents heretofore used.

Other novel features and advantages of our invention will hereinafter appear.

Without limiting our invention or claims thereto, the accompanying drawing, shows for purposes of exemplification, certain special embodiments of the invention:

Fig. 1 is an inside plan view, with parts broken away, of a pad designed to give a Cro- 55

quignole wave by the so called "machine method".

Fig. 2 is a similar view of a pad designed to give a spiral wave by the same method.

5 Figs. 3 and 4 are similar views of pads designed to give a Croquignole and a spiral wave, respectively, by the so called "machineless method".

Fig. 5 is a cross section of my absorbent, taken on line 5—5 of Fig. 1, with the sheets constituting 10 it shown separated for clearness of illustration and the protecting sheet 3 omitted.

Fig. 6 is a similar view showing a modified form of sheet.

Referring to Fig. 1 there is shown a pad 1, designed 15 for Croquignole waving by the machine method, comprising an absorbent 2 and a heat conducting or protecting sheet 3, conveniently of foil, which if desired may be provided with perforations 4 to permit the release of steam. The 20 foil sheet is attached to the upper edge of the absorbent 2 by any suitable fastening means such as staples 5.

The absorbent material is shown in Fig. 5 as comprising 25 six sheets of thin absorbent paper, provided with a preferably flat backing 7 of some pliable reinforcing material such as parchment or the like, having cohesive or tensile strength, the several sheets and backing being here shown as held together by the interlocking effect resulting 30 from an embossing pressure applied against the sheets on the lines 8. This pressure results in a permanent compression of the sheets along the lines 8 between which are the looser pad or cushion-like portions 9 facilitating the absorption and 35 retention of a fluid but readily yielding it when squeezed or pressed. We have shown whipcord embossing but any other desired conformation may be given the surfaces or, as hereinbefore indicated, the sheets may be held together in any 40 other suitable way.

While sheets of plain paper if sufficiently absorbent may be used, we prefer to use crepe paper or paper having similar characteristics because of its greater actual surface area for the same 45 size of sheet and its consequent great absorbing capacity.

Embossing through multiple sheets renders crepe paper more resistant to spreading out when wetted than a single sheet. Therefore, the backing sheet 1 being relatively flat, less yielding and less subject to wetting than the embossed absorbent, also acts to prevent the latter from expanding or spreading out when wetted.

In Fig. 6 we have shown an absorbent made of 50 paper sheets 38 having pockets 39 of special design impressed therein, the sheets contacting each other at 40 and being provided with a backing 41.

In Fig. 2 is shown a pad designed for spiral waving by the machine method. The pad comprises 55 the absorbent 12 attached by suitable means, such as staples 5, to a wrapper shown as composed of two sheets 13 of impervious material, such as parchment or the like, conveniently formed by folding a single sheet at the bottom. Between these sheets is preferably interposed a heat transmitting and protecting sheet of foil 14.

Fig. 3 shows a pad for the permanent waving of hair by the action of an exothermic material contained therein, specially designed for Croquignole 70 waving. The pad conveniently comprises a backing 19 of parchment or similar material, an envelope 20 containing the exothermic material, here shown as provided with perforations 21 and the absorbent 22, conveniently attached at its upper 75 edge between the backing and the envelope by

any suitable means such as glue, which also may be employed to secure the backing to the envelope.

Fig. 4 shows a similar pad, designed for spiral waving, comprising a wrapper 28, conveniently formed of two sheets of parchment, or similar material, folded from a single sheet, to which is attached the envelope containing exothermic material, shown as provided with the perforations, as in Fig. 3, a heat conducting extension 31 conveniently of foil, and the absorbent 32 conveniently attached at its upper edge between the envelope and the wrapper.

In each of these forms it is seen that the structure of our absorbent unit obviates the necessity of employing an additional cover sheet for the absorbent as where flannel or felt is used.

It will be understood that many changes may be made in the forms and features disclosed without departing from the spirit of our invention 20 and that certain features may sometimes be used to advantage without a corresponding use of other features.

We claim:

1. In a hair waving pad, an absorbent comprising 25 superposed sheets of paper secured together by embossing and provided with a flat flexible backing.

2. In a hair waving pad, an absorbent comprising 30 superposed sheets of paper secured together by embossing.

3. In a hair waving pad, an absorbent comprising 35 superposed sheets of crepe paper secured together by whipcord embossing and provided with a reinforcing element.

4. In a hair waving pad, an absorbent comprising 40 superposed sheets of crepe paper secured together by whipcord embossing.

5. In a hair waving pad, an absorbent comprising 45 superposed sheets of paper permanently attached together at a plurality of spaced points, providing free spaces therebetween capable of absorbing a solution or water within and between their respective fibers and of absorbing further solution or water between the respective sheets by capillary attraction.

6. In a hair waving pad, an absorbent comprising 50 superposed sheets of paper having pockets impressed therein and having their surfaces secured in close contact with each other at points on the raised edges of said pockets, said pockets being arranged in reversed positions in corresponding portions of successive sheets.

7. In a hair waving pad, an absorbent comprising 55 superposed sheets of paper having pockets impressed therein, the successive sheets being arranged with respect to each other so that the pockets of one sheet will not be occupied by the material forming the pocket in an adjacent sheet said sheets being permanently secured to each other at points on the raised edges of said pockets.

8. A hair waving pad comprising an envelope containing exothermic material, an absorbent composed of two or more superposed sheets of absorbent paper permanently attached together 60 at a plurality of spaced points providing free spaces therebetween and a backing possessing cohesive strength attached to said absorbent.

9. A hair waving pad comprising an envelope containing exothermic material and an absorbent 70 composed of two or more superposed sheets of absorbent paper permanently attached together at a plurality of spaced points providing free spaces therebetween attached to said envelope.

10. A hair waving pad comprising a protective 75

sheet, an absorbent composed of two or more superposed sheets of absorbent paper permanently attached together at a plurality of spaced points providing free spaces therebetween and a 5 backing possessing cohesive strength covering a free face of said absorbent sheets and permanently attached thereto.

11. A pad for use in the permanent waving of hair having an absorbent composed of a plurality 10 of superposed sheets of absorbent material permanently attached together at a plurality of spaced points, with defined areas therebetween adapted to accumulate a surplus of liquid when said absorbent is moistened.

12. The combination defined in claim 11, in which one of said sheets is provided with a backing 15 possessing cohesive strength.

13. In a hair waving pad, an absorbent comprising superposed sheets of paper attached to 20 each other at a plurality of spaced points and provided with a flexible backing secured to the entire surface of one of said sheets.

14. In a hair waving pad, an absorbent comprising superposed sheets of paper permanently 25 attached to each other at a plurality of spaced points with defined areas therebetween adapted to accumulate a surplus of liquid when said absorbent is moistened.

15. In a hair waving pad, an absorbent comprising superposed sheets of crepe paper permanently attached to each other at a plurality of spaced points with defined areas therebetween adapted to accumulate a surplus of liquid when 5 said absorbent is moistened.

16. In a hair waving pad, an absorbent comprising superposed sheets of paper having pockets impressed therein, said sheets being permanently attached to each other at a plurality of points on 10 the raised edges of said pockets.

17. In a hair waving pad, an absorbent comprising superposed sheets of paper permanently attached to each other at a plurality of spaced points with defined areas therebetween adapted 15 to accumulate a surplus of liquid when said absorbent is moistened, said absorbent being provided with a reinforcing element.

18. A hair waving pad including an absorbent comprising superposed layers of paper capable of 20 being wetted, and a backing sheet of impervious material attached thereto and substantially covering the area of one side of said superposed sheets.
